UNITED STATES PATENT OFFICE.

ERNEST C. STYBERG, OF RACINE, WISCONSIN.

ELECTRIC SWITCH.

Application filed April 27, 1925. Serial No. 26,212.

This invention relates to electric switches. Objects of this invention are to provide an electric switch adapted for connection to a movable portion of a mechanism such for example as one of the operating levers of an automobile, and which is so constructed that it will close an electric circuit such as the stop light circuit at the early portion of the movement of such member, and which will permit a further movement of the switch mechanism without interrupting the circuit thus permitting unhindered operation of the lever of the automobile and maintaining the circuit closed during the entire operation of such lever.

Further objects are to provide an electric switch which is of extremely cheap and strong construction, which may be applied to the automobile as a unit, which is fully enclosed, and which is admirably adapted for the purpose outlined above.

An embodiment of the invention is shown in the accompanying drawings, in which:—

Figure 1 is a view of the switch looking into the interior of the compartment with the cover plate removed.

Figure 2 is a sectional view approximately on the line 2—2 of Figure 1.

The switch comprises a main housing 1 provided with outwardly projecting curved end flanges 2. A cover plate 3 is provided with an upstanding marginal flange 4, as shown in Figure 2, and with integral grommets 5. These grommets are passed through apertures formed in the flange or feet 2 of the main casing 1 and are spun over, as shown in Figure 2, thus securely retaining the parts and providing a closed construction for the switch at the same time providing apertures for the reception of attaching means.

Within the main casing 1 a transverse rock shaft 6 is positioned and rigidly carries an external operating lever 7, such lever being provided with apertures 8 either one of which is adapted to receive the connecting member 9 extending to the operating pedal. The ends of the shaft 6 are upset, as indicated at 10, to definitely position the shaft and prevent its slipping sidewise from the casing. A pair of stops 11 are secured to one side of the casing and are adapted to limit the motion of the operating lever 7. The central portion of the shaft 6 is extruded or pressed outwardly to form a cross-shaped section 12. This cross-shaped

section is forced through the aperture in an insulating strip 13, as most clearly shown in Figure 2, and rigidly engages such strip. The strip 13 may be made of any suitable relatively hard insulating material and carries a rivet 14 whose enlarged heads project outwardly from the faces of the insulating rock arm or strip 13.

A spring 14' is coiled about the shaft 6 and has its looped central portion in engagement with the strip 13 and its free ends contacting with the casing to thus urge the switch towards open position, as shown in Figures 1 and 2.

A pair of spring contact stationary members 15 are positioned on opposite sides of the insulating strip or rock arm 13 and are provided with outwardly turned ends 16. These stationary contacts are further provided with outwardly turned attaching feet 17 contacting with an inner insulating block 18. An outer insulating block 19 is positioned on the outer side of the casing 1 and internally threaded thimbles 20 are passed through the feet and through the blocks, the ends of the thimbles being spun over or flanged to retain the blocks and contact members securely in position.

Spring contact clips 21 are positioned at the outer ends of the thimbles 20 and are held in place and adapted to be closed by means of screws 22, such contact clips being adapted to receive and clamp the conductors thereto.

It is to be noted from Figure 1 that the outer block 19 is provided with a central web 23 against which the sides of the terminal clips are adapted to bear to thus prevent rocking of such clips and also to form an insulating wall between the clips to prevent inadvertent contact or short circuiting of the conductors when they are positioned within the terminal clips.

It is to be noted that a slight play is allowed the operating pedal, such for example as the brake pedal without closing the circuit. However, when the pedal is applied its initial motion closes the circuit by passing the rivet 14 between the spring contact stationary members 15. These members readily spring apart and scrape against the rivet 14. Further motion of the brake pedal or other operating pedal is permitted without opening this circuit as the rivet 14 may rock inwardly a material distance and still remain in contact with the fingers 15.

It will thus be seen that an electric switch has been provided which is eminently suited for automobile work, as described in detail above, which is of simple and strong 5 construction, which is completely closed, which may be readily attached and very simply manufactured.

Although the invention has been described in considerable detail, it is to be understood 10 that the invention may be variously embodied and is, therefore, to be limited only as claimed.

I claim:

An electric switch comprising a metallic 15 casing having a main member provided with side and end walls and with outwardly extending flanges at its ends, a cover plate having upstruck flanges surrounding the outwardly extending flanges and having 20 integral grommets passing through the out-

wardly projecting flanges and secured thereto, a transverse bar extending through the side walls of the main member and having an operating lever on its outer ends, said bar having outwardly swaged portions intermediate its end, said swaged portions being forced through an apertured insulating lever, a rivet passing through the end of said insulating lever, an insulating block carried within said casing and secured thereto, and having a pair of spring fingers adapted for positioning on opposite sides of said insulating lever, said spring fingers having outwardly turned ends adapted to receive between them the heads of said rivet. 25 30 35

In testimony that I claim the foregoing I have hereunto set my hand at Milwaukee in the county of Milwaukee and State of Wisconsin.

ERNEST C. STYBERG.
